BARREL PRINTING APPARATUS

Benjamin R. Newcomb, Bound Brook, and Laszlo M. Stempel, Metuchen, N. J., assignors to John Waldron Corporation, New Brunswick, N. J., a corporation of New Jersey

Application November 4, 1953, Serial No. 390,214

15 Claims. (Cl. 101—38)

The present invention relates to printing presses and more particularly to offset type presses adapted to print over the whole periphery of cylindrical barrels and drums.

It is a general object of the present invention to provide a novel and improved press of the offset type constructed and arranged to print on the complete periphery of cylindrical barrels and drums.

More particularly it is an object of the present invention to provide a novel and improved multicolor offset press adapted to print on the full circumference of a cylindrical barrel or drum during approximately one-half revolution of the blanket cylinder, devoting the remainder of the revolution to removing and replacing the article to be printed and to inking the plate cylinders.

An important object of the invention comprises the arrangement of the press wherein the plate cylinders are of a diameter of the order of that of the article to be printed and the blanket cylinder twice that diameter with only one-half of its circumference used for impression whereby the plates are inked twice for each printing and hence a heavier impression obtained.

Another important object of the invention resides in the provision of mechanism for automatically clamping, rounding and centering a barrel tube for presentation to the blanket cylinder.

A further important object is to automatically detect the presence of a barrel tube and longitudinally position it for registration with the printing apparatus.

A still further object of the invention resides in the provision of pneumatic means for lifting and holding the barrel tube resiliently in contact with the printing blanket whereby eccentricities and inequalities are readily compensated for and good printing contact maintained.

Among essential features of novelty may be enumerated the following:

Automatic detection of absence of barrel tube and suppression of lift of the tube engaging heads to prevent damage to the blanket;

Timing of barrel tube gripping, lifting, lowering and releasing by cams on end of blanket cylinder;

Effecting longitudinal registration of barrel tube with blanket by adjustable stop for full stroke pneumatic gripping cylinder at one end and reduced speed of operation of cylinder at other end of tube;

Provision of separate motor to take press off impression and return it to impression with automatic cycling mechanism for such motor;

Provision of eccentric type alignment mounts for the plate cylinder bearings;

Automatic operation of barrel delivery from gravity feed in unison with printing cycle;

Provision of means to print on a barrel or drum having circumferential bilge runners or hoops.

Other and further objects and features of the present invention will be more apparent to those skilled in the art upon a consideration of the accompanying drawing and following specification, wherein is disclosed a single exemplary embodiment of the invention with the under-

standing that such changes and modifications may be made therein as fall within the scope of the appended claims without departing from the spirit of the invention.

In said drawings:

5 Fig. 1 is a side elevation of a multicolor barrel or drum printer constructed in accordance with the present invention;

10 Fig. 2 is a transverse vertical section thereof taken on broken line 2—2 of Fig. 1 and showing a drum tube (in broken lines) receiving a printing impression;

15 Fig. 3 is a fragmentary view on an enlarged scale showing the pneumatic drum tube engaging and lifting cylinders at one side of the machine, a portion of the lift plunger guide means being broken away to illustrate the stroke limiting mechanism;

Fig. 4 is an enlarged sectional view through a plate cylinder bearing, eccentric mounting and lateral registration means;

20 Fig. 5 is a schematic and diagrammatic illustration of the drum cylinder gripping and lifting mechanism control piping and wiring;

Fig. 6 is a side elevation, on an enlarged scale, of the cams on the blanket drum shaft for putting the press on or taking it off impression.

25 The printing of steel drums or barrels and particularly those of the fifty gallon size and larger has heretofore presented many difficulties, and the best known solution to date consists in printing or lithographing the flat metal sheets, from which the barrel tubes are made, prior to curling them into cylindrical form. The mechanical treatments to which the sheets are submitted subsequent to the printing damages the latter to a considerable degree. In addition to the mechanical forming necessary

30 to provide the tubular configuration, a seam must be formed along one element of the barrel between the abutting ends of the sheet and the working and heat incidental to this operation further damages the printing. It is thus not commercially possible to provide an all-over printed barrel tube without subsequent touch-up operations to take care of portions damaged in the working.

In accordance with the present invention the barrel tubes are printed prior to heading but subsequent to the longitudinal seaming whereby complete circumferential printing may be effected which is not subject to damage

45 by subsequent operations. Although the apparatus has been illustrated with chucks adapted to handle open ended barrel or drum tubes, nevertheless only minor and readily perceptible modifications are necessary to handle complete and headed barrels or drums, and it is the intent of the present application to cover both arrangements.

The printing press for barrel tubes is of the multicolor, offset type, including a cylinder rotatable on a horizontal axis and fitted with a blanket on which multicolor impressions are placed by means of a plurality of plate cylinders each inked in the usual manner with its desired color. The plate cylinders are each of approximately the same diameter as the barrel tubes to be printed, whereas the blanket cylinder on which the printing is done from the plates and from which it is transferred to the barrel tubes is somewhat greater than twice the diameter of the latter, whereby but approximately half of the circumference is covered with blanket. The blanket cylinder is rotated continuously and a new barrel tube

55 substituted for the printed one during the half revolution in which no part of the blanket is presented to the printing position. For convenience and facility in feeding the barrel tubes printing is done at the lowermost point or nadir of the blanket cylinder orbit and the tubes roll on tracks having a slight incline so that they pass beneath the printing apparatus by gravity, and are stopped periodically

by suitable mechanism to permit the printing operation.

The barrel tubes are substantially cylindrical but may be somewhat irregular due to the crudeness of the bending operation forming them or damage in shipping or handling. Their ends are flared for the reception of heads and this facilitates their running on the track without any possibility of rubbing against each other except at the edges of these flanges which also keep the printed portion of the tube off of the tracks so that it is not smeared after printing. Preferably the drum tubes are cleaned and prepared by a preliminary coating of paint or the like to more readily receive the printing ink provided by the present apparatus.

Referring now to the drawings, and particularly to Figs. 1 and 2, for a better understanding of the general arrangement of the apparatus, it will be noted that the printing press is essentially composed of a blanket cylinder 10 carrying on a portion of its periphery a resilient blanket 11 and a plurality of plate cylinders 12, 13, 14 and 15. The number of plate cylinders is dictated by the desired number of colors in the printing and may be more or less than illustrated. These plate cylinders are distributed about the upper half of the periphery of the blanket cylinder and with it have their shafts supported in suitable bearings carried in the side plates 16 and 17 constituting the principal frames of the machine. These plates are parallel to each other, as seen in Fig. 2, and are appropriately attached to and supported by transverse beams 18, two in number, which are themselves supported at a suitable distance above the floor level by means of corner posts or columns 19 which are in turn supported from transverse beams 20 resting on pads 21 supported from a suitable floor or the like. The columns are connected together on each side of the machine and reinforced and braced by longitudinal beam members 22 as seen in Fig. 2.

These brace beams 22 have appropriately secured to their inner flanges the centrally located vertical plates 23 for a purpose to be later described, while secured against the inner flanges of the columns 19 are the angle bars 25 extending longitudinally of the press and constituting the principal members of the drum tube feeding tracks, inclined, as shown in Fig. 1, so that the tubes supplied from the left will move by gravity toward the right under control of mechanism which will later be described. The horizontal flanges 27 of the track angles which support the ends of the tubes are seen in greater detail in Fig. 3, each mounting a tube end guide strip 28. The two guide strips are spaced apart a distance just slightly greater than the overall length of a tube which is to be printed.

Such a tube is shown on an enlarged scale in Fig. 3 at 30 and will be seen to comprise a complete tubular cylinder having the conical end flares 31 spaced apart just the proper distance to conveniently fit between the guide strips 28. The peripheries of these flares roll on the top surfaces of the flanges 27 of the tracks. It will be seen in Fig. 1 that a barrel tube may be stopped on the tracks directly beneath the lowermost point or nadir of blanket travel for printing purposes and may be held in this position until appropriately grasped by chucks, now about to be described, by having barrel tube 32 which has just been printed, held as shown by means of stop lever 33, positioned a distance substantially one and one-half times the diameter of a drum tube from a vertical line through the axis of the blanket cylinder, whereby the drum to be printed is properly positioned beneath the blanket cylinder as shown in Fig. 1. Other drums 34 and 35 on the feed end of the track are prevented from rolling further by the contact of their flange edges with the flange edges of the drum in printing position.

In order to exactly locate each drum tube in respect to the printing cylinder and to elevate the same into contact with the blanket for a printing impression, each tube in its turn is gripped between a pair of frusto-conical chuck

members 38 and 39, facing each other on opposite sides of the printing machine as seen in Fig. 2 and appropriately sized to fit within the tapered ends of the drum tubes. Such chucks may comprise dish-like castings appropriately reinforced by radical webs 40 as seen in Fig. 3 while their conical peripheral surfaces are accurately machined to round out and properly centralize the drum tubes and thus present them as accurately as possible for the printing operation. As seen in Fig. 3, each chuck disc is mounted by means of double row, anti-friction bearings 41 on a stub shaft extension 42 of a piston rod whose piston (not shown) is slidably mounted in horizontally disposed pneumatic cylinders 43, 44 in order to project the chuck for gripping or to withdraw it for releasing the drum tube as desired at the proper times in the cycle of operation of the printing press.

Each of the cylinders 43, 44 is mounted on a separate cradle 45 which is itself attached, as shown in Fig. 3, to an extension 46 on the rod 47 of a piston slidably fitted in vertical cylinder 48, 49 each of which is mounted against the inner face of plate 23 carried by column brace 22 as previously described. These plates also carry the combined guide and stroke limiting mechanisms 50 for each of the vertical cylinders, as best seen in Fig. 3. In this the extension 46 of the piston rod 47 is guided for sliding in the bushings shown. Each rod extension is fitted with a notched portion 52 operating over a fixed abutment 53 secured to the part 50, as shown, to limit the stroke of the piston in each direction in cylinder 48. This abutment 53 is positioned so that the lowermost position of the piston rod 46 rests the cradle 45 against the upper end of block 50 and thus positions the chuck to cooperate with a properly located drum tube resting on the track.

Thus when the drum tube is rolled down to a position determined by the stop 33 and the intervening drum tube 32 it is confronted by the two chuck heads and is at the proper level to receive them when air is let in to the outer ends of the cylinders 43 and 44. This air under considerable pressure projects the chucks at high velocity in order to jam them tightly into the flares of the drum and bring the latter to as nearly a true round condition as possible.

As seen in Figs. 2 and 3 the piston rods 42 in cylinders 43 and 44 extend through the outer cylinder heads and beyond are threaded to receive the adjusting nuts 55 which are split and can be tightened to lock them in position. The one shown in Fig. 2 on the left is set up to limit the inward stroke of the chuck 39 to a stop position which locates the drum tube longitudinally to exactly cooperate with the blanket 11 on the blanket cylinder and insure full length coverage of the printing right up to the flanges on the tube. The stroke adjusting nut 55 on the right hand piston is set for full stroke for a purpose which will be later described and the action of this piston is retarded by reducing the air pressure supplied to it so that full stroke of the left hand piston is achieved before any substantial motion takes place in the right hand chuck assembly. With its reduced pressure the cylinder 43 cannot overcome the registration of the left hand chuck which has reached its stroke limit first.

After the barrel is gripped between chucks and at the proper time in the cycle of blanket rotation the drum tube and its chucks is lifted by means of pneumatic cylinders 48 and 49 into contact with the blanket as shown in Fig. 3 and rotated thereby at the same time that the printing impression is made. At the end of the impression portion of the cycle the pistons in cylinders 48 and 49 are de-energized on their lower faces and energized on the upper to immediately lower the drum tube after which it is released by the chucks and moved away on the tracks to be replaced by a fresh drum for the next printing operation. The cycling of this is in accordance with controls arranged for operation by the blanket cylinder which will be later described.

As seen in Figs. 1 and 2, the side frame members 16 and 17 which support the several cylinders of the press are of irregular shape and each is provided with an appropriate notch 60 and closure plate 61 for rotatably holding the eccentric bearing member 62 for main shaft 63 of the blanket cylinder 10 which is secured to this shaft. The eccentric members 62 are appropriately bushed as shown to journal the reduced ends of shaft 63.

In quite the same manner the respective shafts 65 of the several plate cylinders 12, 13, 14 and 15 are journaled in bushed bearings 66 similarly mounted in the side frames. These bearings 66 are also eccentric since it is the intent that adjustment in a lateral or vertical direction be permitted for any of the plate cylinders. These cylinders as shown are closed on the ends and each is provided with a circumferential bearer 70 at each end which rests on the corresponding bearer 71 on the blanket cylinder and insures proper cooperation between the two and determines the degree of pressure which exists between the plates on the plate cylinders and the blanket covering a portion of the periphery of the blanket cylinder. The plates may be of any desired type prepared by photo-engraving, photolithography, etching or the like and their construction and manner of mounting on their respective cylinders forms no part of the present invention, but it should be pointed out that the circumferential length of the plates is substantially the same as the circumference of the barrel or drum to be printed.

One end of each plate cylinder shaft is provided with means for adjusting it longitudinally in order to insure proper registration between the impressions from the various plates on the respective plate cylinders. This insures location of the various color portions of a pattern to be printed so that they are properly distributed on to the rubber blanket and do not overlap or smear.

Such apparatus is shown in enlarged detail in Fig. 4 where the end of shaft 65 is seen to be fitted with the extension 67 having the radial flange 68 thereon. Before being fastened to the end of the shaft by stud 69 this extension is passed through the races for ball bearings 70 and the opening in the smaller end of cup 71. This cup has the flange on its outer end resting on helical spring 72, surrounding the cup and bearing against the end of shaft bearing bushing 66 thereby through the ball bearing 70 urging the shaft 65 toward the left. This action is counteracted by the thrust disc 73 resting on the outer race of ball bearing 74 whose inner race fits against the flange 68 on the extension 67. The disc 73 is adjustable in position by means of screw 75 threaded into the bottom of cup 76 inverted over spring 72 and having its peripheral flange bolted to bearing bushing 66 as seen in Fig. 1. A lock nut 77 permits securing the screw 75 in any position in which it is adjusted by its capstan handle 78. A smaller capstan handle 79 is provided for the lock nut. It will thus be seen that by loosening the lock nut endwise adjustment of shaft 65 and its plate cylinder is effected as desired and that the latter can be locked in position to insure it remaining as originally set.

Each of the slightly eccentric bearing bushings 66 for the plate cylinder shafts is fitted with a radial arm 80 as best seen in Fig. 1 and this arm is engaged on its opposite faces by screws 81 and 82 carried in a bracket mounted on the face of the frame plates. Adjustment of the two screws provides for slight rotation of the eccentric bush and adjustment of the position of the plate cylinder. These various adjustments are provided so that all of the plate cylinder bearers can be made to engage with equal pressure against the blanket cylinder bearers. When these adjustments are once made they remain fixed except to compensate for wear in the bearings.

The plate cylinders are each inked by a suitable ink supplying and distributing mechanism 85 and only several of these are shown in any detail. They need not be here described since they can be of conventional construction and serve merely to supply a uniform and accu-

rately distributed supply of appropriately colored ink to the plates on the plate cylinders in a manner well known. The several inking mechanisms are fulcrumed between the side plates 16 and 17 at positions corresponding to that numbered 86 in Fig. 1. Near the opposite side of each of the inking mechanisms is a pair of pads 87 adapted to rest on eccentrics 88 on shaft 89 extending between the side plates of the mechanism. These various shafts 89, one for each of the inking devices, is each equipped with one or more crank arms 90 to which are attached operating links 91 for rotating the shafts and thus the eccentrics to lift the inking devices out of contact with the plate cylinders when the press is taken off impression. Additional, independently actuatable hand cranks are also supplied for the convenience of the printer.

The several links 91 have their opposite ends connected to crank arms on adjacent shafts 89 so that three of the inking mechanisms may be lifted under the action of link 92 while the fourth responds to link 93. Links 92 and 93 are connected respectively to two arms of a multi-crank lever having a third arm 94 connected by link 95 to radial arm 96 on the eccentric bushing 62 for the shaft 63 of the blanket cylinder.

These eccentrics 62 have a substantial throw so that when the multi-crank lever having the arm 94 is partially rotated in one direction movement is imparted to the eccentric bearing bushings in a direction to lower the blanket cylinder and withdraw it from contact with all of the plate cylinders simultaneously. This happens at the same time that the multi-crank lever actuates links 92 and 93 to lift all of the inking mechanisms from contact with their plate cylinders. This operation will be understood by those acquainted with the use of offset printing presses of this general character and is for the purpose of preventing ink ridges forming between contacting rolls and/or cylinders when the press is idle.

The power to take the press off "impression" or to return it to "impression" comes from a small electric motor 98 shown in Figs. 1 and 2 as resting on platform 99 supported from the side frames at the right hand of the press. This motor through an appropriate coupling drives the worm reducer 100 whose output shaft is fitted with a crank pinned to link 101 connected to one of the arms on multi-crank lever 94. Mechanism, later to be described, limits operation of the motor so that the crank on the shaft of worm reduced 100 makes but half a revolution for each cycling operation. One such operation serves to rock the multicrank lever to lift all of the inking mechanisms from the plate cylinders and to lower the blanket cylinder from contact with the plate cylinders, while the other half revolution restores the parts to operating condition.

The main drive for the press is shown as motor 105 mounted on a suitable platform carried by channel beams 106 which supports stub beam 107 holding the base of the motor. The motor is provided with a pinion engaging a bull gear 108 on the end of shaft 63 for the blanket cylinder, this being outside of frame plate 17 and meshing individually with gears 109, one on the shaft of each of the plate cylinders. The gears 109 are each rotatably adjustable on its shaft for impression registration by means of mechanism shown at 109'.

As previously mentioned the circumferential extent of the plates on the plate cylinders is the same as the circumference of the drum to be printed. The blanket covers slightly more than 180° of the circumference of the blanket cylinder and is of a length to insure taking the full impression from the plates on the plate cylinders. The gearing just described is so adjusted and timed that each plate cylinder makes its impression at the proper place for exact registration of the several colors on the surface of the plate-length blanket on the blanket cylinder. Since the blanket cylinder makes one revolution for each drum printed it imparts two revolutions to each of

the plate cylinders for each drum printed and this provides them with a double inking, insuring an extremely heavy coating of ink being applied to the blanket for transfer to the drum.

The motor 105 for the main drive of the press is provided with appropriate starting and stopping control circuits actuated by the usual push buttons and provided with the desired safety mechanisms, none of which form any particular part of the present invention, but circuits for motor 98 are so interlocked with those of motor 105 that the pressing of the "stop" button for the main motor causes motor 98 to operate and provide one-half cycle of movement to the mechanism which takes the press off "impression" to insure against the press coming to a stop with any contact between the plate and blanket cylinders or between the plate cylinders and the inking mechanisms. As seen in Fig. 1, the worm reducer mechanism 100 is provided with a cam 110. This cooperates with switches (not shown) in the circuit of motor 98 to stop it, after each start, at the end of one-half revolution of cam 110. Mechanism and circuits for this type of operation are old and well known, see Patent 2,464,389 for showing. The half cycle operation initiated by the stop button for motor 105 is followed by a half cycle operation to return the press to "impression," initiated by operation of the "start" button for motor 105.

The shaft 63 of the blanket cylinder is provided with a pair of cams 111 and 112 arranged to cooperate with switches (not shown). The first of these cams insures that motor 98 can only be started at a time in the cycle when the blanket cylinder is not in contact with any plate cylinder to take the press off "impression." The second cam insures that the motor 98 can be started only at a time in the press cycle when the blanket cylinder is in a position remote from "contact" with any plate cylinder to put the press on "impression." After each start under the control of cam 111 or cam 112, cam 110 comes into play to limit the movement of the shaft of the worm reducer to one-half revolution.

While it has been found that the cams on the shafts of the worm reducer and the blanket drum provide adequate accuracy for the operations just described, it is deemed essential to provide greater accuracy in the locating of operating mechanism for determining the cycling of the gripping cylinders for the drum chucks and the elevating cylinders for the same and therefore the operating cam lugs controlling the switches for these devices are located on one head of the blanket cylinder. As shown in Fig. 1 the right head is equipped with four cam lugs, numbered respectively 115, 116, 117 and 118. The first two of these cooperate respectively with switches 119 and 120 shown mounted on arm 121 at the left in Fig. 1 and supported from beam 18, while the second pair of cam lugs cooperate respectively with switches 122 and 123 supported by arm 124 from the opposite beam 18.

Reference will now be made to Fig. 5 illustrating diagrammatically and schematically the air and electric circuits for operating the chucks for the drum tubes. In this figure the chucks 38 and 39 are shown mounted on the piston rods of cylinders 43 and 44 respectively. The source of air supply under relatively high pressure is illustrated at 130 and air from this is delivered to each of the similar distributing valves 131 and 132 respectively. The first of these controls the delivery of air to the horizontal cylinders 43 and 44 for gripping or releasing the chucks. From the left end of distributing valve 131 air line 133 leads to the outer ends of cylinders 43 and 44, a pressure reducing valve 135 being provided in the branch line to the outer end of cylinder 43, whereby this cylinder moves its piston more slowly than does cylinder 44 as previously described. From the opposite end of distributing valve 131 air line 136 leads directly to the inner ends of the two cylinders 43 and 44.

The operating plunger of distributing valve 131 is under control of the two solenoids 137 and 138. When solenoid

137 is energized the valve plunger moves to the left and distributing valve 131 supplies fluid to the outer ends of cylinders 43 and 44, causing the chucks to advance toward each other and grip a drum tube from the tracks, operating in the manner already described to properly position this tube longitudinally in respect to the edges of the printing blanket. When the plunger of distributing valve 131 is moved toward the right under the action of solenoid 138 air is released from the outer ends of cylinders 43 and 44 and admitted to the inner ends so that the chucks are drawn apart and the barrel released.

Solenoid 137 is under control of switch 119 which energizes it when the switch is closed by cam lug 115. As seen in Fig. 1, with counterclockwise rotation of the blanket cylinder, this lug engages switch 119 first and causes the gripping of a drum tube during the interval following the passing of the trailing edge of the blanket by the nadir so the space beneath the cylinder is free for the movement of the drum to be printed. As the leading edge of the blanket approaches the nadir cam lug 116 closes switch 120 which will be seen in Fig. 5 to move the plunger of valve 132 to the left, thereby energizing air line 140 and supplying compressed air beneath the pistons of vertical cylinders 48 and 49, simultaneously lifting the chucks and providing a resilient urging of the drum against the cushioned blanket where it is held during the half revolution necessary to complete the impression thereon. When this position is reached cam lug 117 engages and closes switch 122 drawing the plunger of distributing valve 132 to the right, charging air line 141 and releasing air from line 140. This causes the cylinders 48 and 49 to lower the chucks simultaneously, setting the drum back on its track. Almost instantly, then, cam lug 118 engages switch 123, causes movement of the plunger of distributing valve 131 to the right, energizing air line 136 and releases the chucks from engaging with the drum cylinder.

As previously mentioned, provision is made to insure against lifting of the chucks in event of absence of a drum tube between them since under these circumstances and at full inward stroke their edges might damage the blanket. The absence of a drum between the chucks is detected by measuring the over extension of the piston rod on which chuck 38 is mounted. This is achieved by providing a striker 145 thereon, which, when the chuck reaches the limit of its inward movement, engages and opens switch 146, which opens the circuit of the lift solenoid energized normally by closing of switch 120. Even though this latter switch is closed by its cam lug on the blanket cylinder the solenoid is not energized. A manual manipulation to return the chuck or its return by the release lug 118 reconditions the system for normal operation.

In the early part of this specification stop lever 33 was mentioned, and it is illustrated in Fig. 1 in solid line position where it engages the last printed drum as it rolls down the track and holds it in the position where it will stop the following, but unprinted drum, directly beneath the bottom of the blanket cylinder ready to be engaged by the chucks prior to printing. This lever is pivoted at 150 to a pillow block on one of the standards of the press. A second arm 151 secured to the lever 33 is connected by adjustable link 152 to the piston rod of cylinder 153 which is pneumatically operated to shift the stop lever between the solid line position and the dotted line position. The mechanism for operating this cylinder comprises a pair of solenoids and a selector valve for delivering air to one end or the other of cylinder 153, the construction being exactly identical with one of the showings of Fig. 5, associated solenoids and control switches being provided in an obvious manner. Switch tripping lugs may be provided on one head of the blanket cylinder. Further illustration is not deemed necessary. The operation of lever 33 is obvious. After a drum tube is printed and released by the chucks lever 33 is lifted to dotted line position just long enough to release the drum plate tube in

position 32 after which it is returned to the stop position to prevent further rolling of tube 30 beyond the position number 32. This allows a fresh tube to be positioned in the printing position.

In some cases it may be desirable to print directly on the surface of a drum tube which has already been provided with circumferential ridges or bilge runners, on which the barrel may be rolled, and which serves to reinforce it against distortion on impact or the like. Under these circumstances the apparatus is provided with mechanism for spacing three parts of a blanket longitudinally along the drum to leave unblanketed areas for clearance over these bilge runners. The plates may or may not be divided in a like manner as circumstances dictate. The peripheries of the bilge runners may be inked subsequently, or by an attachment to the above described press, or they may be left with only the initial coating thereon.

We claim:

1. Mechanism for printing on the whole cylindrical surface of a large diameter, open ended steel tube adapted to be formed into a drum comprising in combination, a blanket cylinder having substantially one half its periphery covered by a blanket, means for mounting and driving said cylinder continuously, a plate cylinder having a plate sized and positioned for transfer contact with substantially all of the blanket surface and driven in unison with the blanket cylinder, continuous inking means for the plate, means for advancing contiguous tubes one at a time beneath said blanket cylinder during each non-printing half revolution of the blanket cylinder, power actuated means to engage and round out the tube directly beneath the cylinder, and means to subsequently pneumatically lift the last mentioned means and tube and present the latter in printing contact with the blanket, the drum and plate cylinder being of substantially the same circumference and the blanket cylinder being of twice the plate cylinder circumference.

2. The printing mechanism of claim 1 in which the said pneumatic means is timed to lift the drum for printing by means on and associated with the blanket cylinder for proper synchronization.

3. The mechanism of claim 2 in which means is provided associated with the said power actuated means to detect the absence of a drum beneath the blanket cylinder, and mechanism associating said last mentioned means and the pneumatic lifting means to prevent the energization of the latter in the absence of a drum.

4. A press for printing on the whole circumference of a cylindrical drum comprising in combination at least one plate cylinder of slightly greater diameter than the diameter of said drum and having a printing plate thereon covering substantially the full circumference thereof, means for continuously inking said plate, a blanket cylinder twice the diameter of the plate cylinder and having a blanket thereon just large enough to accept the impression from the plate, means continuously rotating said cylinders at identical peripheral speeds about horizontal axes, means to advance a line of contiguous drums in one drum steps at each passage of the unblanketed portion of the blanket cylinder below its axis, means engaging the outer peripheries of the drum ends to receive a drum beneath and spaced from said blanket cylinder, a pair of facing conical chucks spaced to clear both ends of said drum and rotatable about an axis parallel to said axes, means to simultaneously axially advance said chucks to engage said drum between them on said drum holding means, and means to subsequently elevate said advancing means and chucks to contact the drum with the blanket for rotation thereby and printing.

5. The press as defined in claim 4 wherein one of said chuck advancing means has an adjustable stroke limiting device and is advanced prior to the other to determine longitudinal registration of drum and blanket.

6. The press of claim 5 wherein the advancing means

are pneumatic and the one for the other chuck is supplied through a pressure reducer to effect delay in advancing.

7. The press of claim 6 wherein the said other chuck advancing means is equipped with an excess stroke detector, said chuck elevating means being arranged to be rendered ineffective on actuation of said detector to prevent damage to the blanket by the chucks.

8. The press of claim 4 in which the chuck advancing means comprise pneumatic cylinders and pistons whereby constant contact pressure is effected between blanket and drum in spite of out-of-roundness of the latter.

9. The press of claim 4 in which the drum is headless and the chucks are truncated cones, the advancing of said cones into the ends of the drum serving to lift it from the receiving means insufficiently to engage the blanket and to bring it into roundness, and means to withdraw the chucks after the drum has been printed and lowered, said withdrawal means being under control of a cam on the blanket cylinder.

20 10. In a printing press of the type described, in combination, a blanket cylinder mounted for continuous rotation and having approximately one half its circumference covered with printing blanket, power means to drive said cylinder, means to elevate a drum and hold it against said

25 blanket during the passage of the latter past the nadir, means to change drums during the passage of the unblanketed portion of the cylinder, a plurality of plate cylinders arranged about the upper half of the blanket cylinder and each having a plate adapted to transfer an impression to the blanket, inking means for each plate cylinder, means to drive the plate cylinders from and at the same peripheral speeds as the blanket cylinder, mechanism actuated by an operation leading to stopping of the press drive power to lower the blanket cylinder and elevate the inking means to take the press off "impression" which includes an electric motor and speed reducer having an output shaft, a crank on said shaft for effecting said lowering and elevating, a control for said motor limiting its movement per initiation to one-half revolution of said crank and a cam on said crank shaft for operating said control, and means to effect such blanket cylinder lowering at a position in its cycle when the blanket is out of contact with all cylinder plates.

45 11. The press of claim 10 where said crank shaft mounted cam limits the shaft to one half revolution when putting the press on "impression" and means to limit said putting on impression to a period in the press cycle when the blanket is positioned to not be contacted by the plate cylinders.

50 12. The press of claim 11 wherein the means to control the period in the press cycle in which the press is put on "impression" is a cam on the shaft of the blanket cylinder.

55 13. A chuck system for gripping a cylindrical drum supported on a runway and advancing the same against a printing member for rotation thereby and printing therefrom comprising in combination, a pair of chucks fashioned to engage the opposite ends of a drum and facing each other on opposite sides of said runway, a carrying and advancing means for each of said chucks, a pneumatic cylinder, piston and rod construction supporting each chuck-carrying and advancing means, said pneumatic cylinder adapted to urge a chuck held drum resiliently into contact with the printing cylinder and means actuated in response to printing member cycle position to control the operation of said cylinder.

60 14. The chuck system of claim 13 in which the chuck carrying and advancing means each comprises a pneumatic cylinder, piston and piston rod, a source of compressed air connected to said cylinders, means to adjust and limit the advancing movement of one of said chuck advancing cylinders and means in the supply line of only the other chuck advancing cylinder to reduce its speed

75 of advancement whereby the first said cylinder advances

11

its chuck to the adjusted limit to effect longitudinal drum location.

15. The chuck system of claim 14 in which detector means is provided for excess stroke length of the second chuck advancing cylinder, actuation of said detector serving to prevent the supply of fluid to the chuck lifting cylinders to prevent the damaging of the printing cylinder in the absence of a drum between the chucks.
